BOILER

Application filed December 14, 1927. Serial No. 239,969.

This invention pertains to boilers of the type employed for domestic heating and relates more particularly to a boiler of sectional type, although in some of its broader aspects it is applicable to boilers of other kinds. Among the objects of the invention are to provide a boiler of unit construction such that two sections suffice to form a complete boiler of practical size but which is capable of enlargement by small gradations to any desired degree merely by the addition of other sections of standard shape; to provide a boiler of the above type in which the ash pit structure consists of standard parts which may readily be assembled to provide an ash pit of any desired size; to provide a boiler in which air is admitted to the combustion chamber in a highly advantageous manner to ensure complete and efficient combustion; to provide for ready application of a refractory or insulating lining to the walls of the firebox; and in general to provide a boiler of simple, durable and efficient character.

In the accompanying drawings in which I have illustrated one desirable embodiment of the invention by way of example:—

Fig. 1 is a front elevation of the improved boiler, with certain parts broken away and in section;

Fig. 2 is a vertical section, substantially on the line 2—2 of Fig. 1 and illustrating a complete boiler consisting of a front section and rear section only;

Fig. 3 is a rear elevation of the boiler;

Fig. 4 is a section similar to Fig. 2 but showing a boiler comprising front, rear, and intermediate sections;

Fig. 5 is a fragmentary section substantially on the line 5—5 of Fig. 4;

Fig. 6 is a fragmentary vertical section, to larger scale, illustrating means for securing the lining of the fire-box in position; and

Fig. 7 is a fragmentary vertical section through the side wall of the ash pit showing details of construction.

Referring to the drawings, the boiler proper is designated by the numeral 1, and the ash pit structure, upon which the boiler proper rests, is indicated by the numeral 2. Referring particularly to Fig. 2, the boiler proper

consists of the front section 3 and rear section 4. The front section 3 is a hollow casting having the front wall 5 and the inner or rear wall 6, spaced apart to provide the main steam and water space 7 and the water leg 8 which partly surrounds the fire-box. The front section 3 is provided with a fuel door 9 giving access to the combustion chamber 10, the front half of which is defined by the inner wall 6 of the front section 3. The inner wall of this front section also defines the front half of the fire-box 11 and the forward portion 12 of the smoke flue which leads upwardly and rearwardly from the forward part of the combustion chamber.

The rear section 4 is also a hollow casting comprising the rear wall 13 and the forward or inner wall 14, spaced apart to provide the main steam and water space 15 and the depending water leg 16 disposed at the rear of the fire-box. The inner wall of this rear section is so shaped as to form the rear half of the combustion chamber and of the firebox and this section is provided with a passage 17 constituting the rear part of the smoke flue. This passage 17 extends from front to rear through section 4 and opens at its rear end into a smoke bonnet 18 secured to or integral with the rear wall 13 of the rear section. This smoke bonnet 18 provides an attachment for the smoke pipe 19 leading to the stack.

The bonnet 18 may be provided with the usual smoke damper 20 and cold air inlet door 21. The parts 20 and 21 are connected respectively to links 22 and 23 which are actuated by a lever 24 operated by a diaphragm within a housing 25 which communicates with the steam space 15.

The rear section 4 is also provided with one or more openings or passages 26 leading from the back of the section into the combustion chamber 10 at a point substantially opposite the fuel door 9, the latter being imperforate and without the usual damper controlled air inlet. The passage 26 is controlled, for example, by means of a sliding damper 27 moving in suitable guides carried by the rear wall 13 of the section 4 and this slide damper 27 may be provided with any suitable type

of actuating handle 28 by means of which the damper may be operated by hand or by connections to the lever 24 or other suitable automatic controlling device.

5 The front section 3 is preferably provided at its upper part with an interior partition or septum 29 (Figs. 2 and 5) projecting rearwardly from its front wall 5 into the steam space 7. This wall or septum 29 is preferably centrally disposed with reference to the 10 width of the front section and is preferably integral with the wall 5 and provides a vertically extending standpipe space 30. This space 30 communicates with the steam space 15 7 by means of small openings 31 and 32 at its upper and lower ends and the space 30 is adapted to take the place of the usual exterior standpipe commonly attached to boilers of this type to provide a body of water 20 which is quiescent and whose level is not substantially affected by the boiling of the water within the main steam chamber. The wall 5 is provided with screw-threaded openings leading into the standpipe space 30 near the 25 top and bottom of the latter respectively for the reception of gage tubes 33 and 34 leading to the upper and lower ends respectively of a gage-glass or water column 35. The front wall of the section 3 is also furnished with 30 suitable threaded openings for the reception of try-cocks 36 and 37 which communicate directly with the steam space 7.

Preferably the front section 3 is provided with a threaded opening at its top for the 35 reception of a steam gage siphon T, which is disposed in the steam space 7. This siphon has a trap chamber communicating at one end with the steam space 7 and at its upper end with a tube leading to the usual steam 40 gage G. This siphon, being disposed wholly within the boiler, is concealed from view, is not as liable to freezing as an exposed siphon and is protected from injury, while at the same time the pressure gage may be placed much closer to the upper surface of 45 the boiler than is usual.

The front and rear sections 3 and 4 are provided with complementary contact surfaces adapted to fit closely together and are united 50 by means of the usual nipples 39 of which but one is herein illustrated.

In accordance with the present invention that portion of the inner wall 14 of the rear section 4 which embraces the fire-box is furnished with an offset 14^a providing a recess 40 (Fig. 6) for the reception of refractory or insulating lining. This recess 40 is preferably provided with a substantially horizontal lower surface but has an upstanding 55 lip or retaining element 41 at the forward edge of said surface. The upper wall 42 of the recess 40 is preferably inclined rearwardly and downwardly and is furnished at its forward edge with a depending lip or 60 retaining element 43. This lip 43 is longer 65

than the lip 41, as shown in Fig. 6. The recess 40 is adapted to hold insulating or refractory material 44, for example fire-brick, fire clay or the like, which is conveniently though not necessarily provided in the form of a brick or slab, and in inserting such a slab in position the upper edge of the slab is pushed up behind the lip 43, as shown in broken lines in Fig. 6 until its lower edge can be swung rearwardly across the top of the lip 41. The slab is then permitted to drop vertically until it rests upon the horizontal bottom surface of the recess with its upper end disposed behind lip 43. The block is thus securely retained in position, although removable by a reversal of the above process. If plastic fire clay is used instead of the slab, the lips 41 and 43 serve equally well to retain it in place. The slab or clay serves to insulate the fire-box from the relatively cold water contained in the water leg which surrounds the fire-box and uniform combustion of the fuel and a uniform level of the fire bed may thus be maintained, which is sometimes difficult when there is a free transfer of heat between the fire and the water leg of a boiler section.

The ash pit structure preferably comprises a front member 45, which is conveniently a casting, and a rear member 46 which is also a casting. The front member 45 is furnished with the usual ash door 47, while the rear member 46 has an air inlet door 48. This door 48 may be connected by means of a chain 49 with the damper 20 so as to be 100 moved in proper relation to the latter by means of the lever 24. The grate bars 50 are supported by the front and rear members 45 and 46 and may be actuated for shaking by means of a link 51 connected to a shaker 105 lever 52 mounted on a bracket 53 carried by the front member 45.

Each side wall of the ash pit structure preferably consists of a length 54 of standard channel bar having upper and lower 110 flanges 55 and 56 (Fig. 7) which are turned inwardly. These flanges 55 and 56 provide convenient means for supporting a refractory or heat insulating lining 57 such as is commonly employed in an ash pit of a boiler 115 which is heated by other than solid fuel, for example a gas or oil burner. While a section of channel shape is preferred for this purpose, it is obvious that standard shapes of other types may be employed, if desired. 120 The sections 54 are attached to the rear and front members 45 and 46 by any suitable form of connection usual in boiler construction.

The boiler thus constructed, as shown in 125 Fig. 2, is complete in itself, comprising the fire-box, combustion chamber, flue spaces, water spaces and ash pit, it being noted that the boiler proper consists of but two sections which are directly connected together. This 130

boiler, consisting of two sections, is complete in itself and represents the minimum size of boiler employing sections of given dimensions.

Referring to Fig. 4, I have shown a boiler of the same general type as that shown in Fig. 2 but of greater capacity. This boiler comprises the same front and rear sections 3 and 4, as shown in Fig. 2, these sections constituting standard units adapted to be used in boilers ranging from the minimum to the maximum size. In order to provide a boiler of greater size than that shown in Fig. 2, I employ intermediate sections such as the sections 58, shown in Fig. 4. Each section 58 is so shaped as to provide a steam and water space 60, one or more flue sections 61, one or more passageways 61^a providing additional heating surface, a combustion chamber section 62, a fire-box section 63, with its corresponding water leg portion, and with front and rear surfaces adapted to fit snugly against one another when such sections are juxtaposed, or against the rear face of a front section 3, or the front face of a rear section 4. These intermediate sections are furnished with proper openings for the reception of connecting nipples 39^a, 39^b, 39^c, etc. by means of which they are secured to one another and to the front and rear sections 3 and 4, it being understood that other nipples (not shown) will be supplied at the proper points. Obviously one or more of these sections may be interposed between the sections 3 and 4 to provide a boiler of the desired capacity.

In the same way the ash pit structure comprises the standard front unit 45 and the standard rear unit 46, and the standard channel members 54 forming the side walls.

In order that sectional boilers may be varied in size by small gradations to correspond with different heating requirements, it is common to make the individual sections of small capacity, sections of 4½ inches thickness being very generally used. In building a boiler by assembling such sections it is substantially necessary to use at least four sections in order to provide a grate area of a practical size to maintain combustion of fuel, but the manufacture and assembly of four such sections involves a very considerable amount of labor and expense including the production of cores, the molding and casting operation, and the machining of four individual sections. In accordance with the present invention I make the front and rear sections of sufficient thickness, for example about double that of usual sections, so that each may have room for at least one grate bar, the combined front and rear sections alone being sufficient to form a complete boiler as above described. Thus the minimum size boiler (having reference to sections of a given type, width and height) con-

sists of but two sections instead of four, thus very materially lessening the cost of making and assembling the parts, while by interposing intermediate sections of usual (4½ inch) thickness between the front and rear sections, boilers of larger size, but graded in conformity to usual practice, may readily be constructed. While I have stated that sections of 4½ inch thickness may be used as the intermediate sections, it is obvious that sections of any desired thickness may be placed between the front and rear sections, although for fine gradation in size and convenience in manufacture the smaller standard sections are more practical.

By using front and rear sections of substantially double the thickness of usual sections, I also provide room for the internal standpipe and adequate steam space in the front section, and obtain plenty of room in the rear section for the smoke flues and steam space, the large flue area in the rear section permitting the use of a smoke bonnet of minimum size.

Whether the boiler be of minimum size, as shown in Fig. 2, or of a larger size, as shown in Fig. 4, the products of combustion from the combustion chamber move forwardly and upwardly into the space 12 and thence rearwardly through the flue 17 into the smoke bonnet 18. Although each intermediate section may be provided with a plurality of spaced flues 61, 61^a, etc., I prefer to supply but a single flue 17 in the rear section, since in this way the size of the smoke bonnet 18 may be kept at a minimum. Thus the flue 17 may, if desired, comprise a plurality of branches merging rearwardly into a single main flue, but ordinarily a single wide flue, converging toward its rear, if desired, is adequate for the purpose. The supplementary air supply, necessary for complete combustion, is admitted through the openings 26, regulated by the damper 27, and this air moves forwardly through the combustion chamber so as to obtain a maximum admixture of the air with the products of combustion before they enter the smoke flue 12. A much greater efficiency of combustion is thus obtained than though the supplementary air supply were admitted through the fire-door 9; even when burning high volatile coal the smoke is reduced below the allowance of usual smoke prevention ordinances; and the heating efficiency of the boiler is greatly increased. As above pointed out the lining of the fire-box with refractory material assists in maintaining a uniform rate of combustion level of fuel bed over the entire fire-box, and the arrangement of the air inlet door 48 at the rear of the ash pit makes it extremely convenient for automatic control. The disposal of the standpipe 30 and the gage siphon T within the boiler improves the appearance of the boiler, lessens the danger of injury to

these parts, simplifies the construction and lessens the cost, while the employment of the standard front and rear sections for the boiler and ash pit and the standard intermediate boiler sections permits ready assemblage of boilers of different capacities at a minimum cost and trouble.

While I have herein described one desirable embodiment of my invention, I wish it to be understood that various changes in details of construction, arrangement and proportion of parts and the substitution of equivalent elements for those herein disclosed are to be considered as within the purview of the present invention as defined by the claims.

I claim:

1. A boiler of the class described comprising assembled transverse sections, each section being of integral unitary construction having spaced inner and outer walls defining a steam and water space between them, the inner walls of said sections collectively defining a combustion chamber and being recessed below the combustion chamber for the reception of refractory material defining the inner surface of a fire box, the effective areas of the fire box and combustion chamber being substantially equal, the assembled sections having passages defining an educt flue leading directly from the upper part of the combustion chamber in the front section rearwardly through all of the other sections, and a bonnet secured to the rear section and communicating with the flue passage in the latter.

2. A boiler of the class described comprising assembled transverse sections, one of the sections being a front section of integral one piece construction having spaced inner and outer walls defining a steam and water space, the inner wall of said front section being shaped to define the front part of a combustion chamber, said section having a door opening directly into the combustion chamber, the upper part of said inner wall being curved rearwardly to define the front part of a smoke flue and the lower part of the inner wall having a recess, refractory lining material within said recess, and a grate bar extending transversely across said section at its lower part.

3. A boiler for domestic heating purposes comprising assembled transverse front and rear sections, said sections having complementary surfaces adapted collectively to form a complete combustion chamber, the front section having spaced inner and outer walls defining a steam and water space, the inner wall of said front section being shaped to define the front part of a combustion chamber, the upper part of the inner wall of the front section being shaped to define the front part of an educt flue, a door in said front section opening directly into the combustion chamber, the inner surfaces of said

sections below the combustion chamber being recessed for the reception of refractory lining material defining a fire box of substantially the same superficial area as that of the combustion chamber, and an intermediate section adapted to fit between the front and rear sections, said intermediate section having surfaces adapted to cooperate with the surfaces of the front and rear sections in defining a combustion chamber of increased area and also to provide a portion of the educt flue and having recesses for the reception of refractory lining material adapted to cooperate with that of the front and rear sections in forming a fire box of increased area.

4. A boiler of the class described comprising a casing or shell defining a combustion chamber, the shell having a normally closed opening leading into the front of the combustion chamber and an air admission opening leading directly through the shell from the outer atmosphere into the rear of the combustion chamber, and an educt flue leading from the forward upper part of the combustion chamber and outwardly through the rear of said shell.

5. A boiler of the class described comprising assembled transverse front and rear sections, said sections having complementary parts adapted collectively to form a complete fire box and combustion chamber, said sections having interior surfaces defining an educt flue leading from the front of the combustion chamber rearwardly and out through the rear section, the rear section having a second passage leading from the outer air directly through it to the rear part of the combustion chamber, and a movable damper for regulating the amount of air entering through said second passage.

6. A boiler of the class described comprising a front section and a rear section, said sections having complementary parts adapted collectively to form a complete fire box and combustion chamber, said sections having cooperating portions providing an educt flue for the products of combustion leading upwardly and rearwardly from the front of the combustion chamber, the rear section having an air admission opening leading directly through it from the outer air into the rear part of the combustion chamber at a point adjacent to the top of the fire box.

7. A boiler of the class described comprising a front section of integral one piece construction having spaced inner and outer walls defining a steam and water space, the inner walls being shaped to constitute the front portion of a combustion chamber and to define the front portion of a rearwardly extending educt flue leading directly from the top of the combustion chamber, said inner wall below the combustion chamber being recessed to receive refractory lining material defining the

- front portion of a fire box, and at least one section assembled with said front section to form therewith a complete combustion chamber, educt flue, and fire box, the educt flue leading rearwardly from the front section and out through the rearmost section, the latter section having a passage through it leading directly from the outer atmosphere to the combustion chamber.
8. A boiler of the class described comprising assembled transverse sections, one of said sections being a rear section of integral one piece construction having spaced inner and outer walls defining a steam and water space, the inner wall being shaped to define the rear part of a combustion chamber, said rear section having an air admission opening leading from the outer air directly to the combustion chamber, a movable damper for determining the effective area of said opening, said section also having an educt passage extending through it from front to rear above the combustion chamber, the inner wall of said section having a recess at its lower part for the reception of refractory material defining the inner surface of a fire box, and a grate bar extending transversely across said section at its lower part.
9. A boiler of the class described comprising assembled transverse sections including a front section defining the front parts of the combustion chamber and educt flue, a rear section defining the rear part of the combustion chamber and the outlet end of the educt flue, and at least one intermediate section, the intermediate section being of one piece construction having spaced inner and outer walls defining between them a steam and water space, the inner wall being shaped to define an intermediate portion of the combustion chamber and an intermediate portion of the educt flue, the inner wall of said intermediate section being recessed below the combustion chamber for the reception of refractory material defining the inner surfaces of an intermediate portion of a fire box, the front and rear sections each having a passage therethrough leading directly into the combustion chamber.
10. A boiler of the class described having an ash pit structure comprising a front member, a rear member, and side members uniting the front and rear members, said side members consisting of channel-bars with their flanges turned inwardly and adapted to hold a refractory lining.
11. A boiler of the class described comprising a front section and a rear section, said sections having complementary parts adapted collectively to form a complete fire-box and combustion chamber of small size, an intermediate section adapted to fit between said front and rear sections, said intermediate section having a portion cooperating with the front and rear sections to form a fire-box of a greater size, an ash pit structure supporting said sections and comprising a front member having a door, a rear section, and side walls uniting the front and rear sections, each side wall comprising a length of channel bar with its flanges directed inwardly and refractory lining material interposed between said flanges.
12. A boiler of the class described comprising a front section consisting of an integral casting having spaced front and rear walls defining a main steam and water space, the rear wall being shaped to form the front portion of a combustion chamber, smoke flue, and fire box, the front wall of said section having at its upper part an integral interior septum projecting into the main steam space, said septum defining a vertical stand pipe space, and having openings at its top and bottom providing communication between the stand pipe space and the main steam space, the front wall having screw-threaded openings leading into the stand pipe space near the top and bottom respectively for the reception of gage tubes.
13. A boiler of the class described comprising assembled transverse sections one of said sections being a front section and another being a rear section, each of the sections being of integral one piece construction having spaced inner and outer walls defining a steam and water space, the inner wall of the front section being shaped to define the front part of a combustion chamber and the entrance to an educt flue, said front section having a door opening directly into the combustion chamber, the lower part of the inner wall of the front section having a recess for the reception of refractory lining material and the rear section having a passage defining the rear end of the educt flue and another passage leading directly from the outer air to the combustion chamber.
- Signed by me at Westfield, Mass., this 29 day of November, 1927.
- STANLEY K. SMITH.
